UNITED STATES PATENT OFFICE.

GERALD FOLL, OF WINNIPEG, MANITOBA, CANADA, ASSIGNOR OF ONE-HALF TO JOSEPH YOUNG, OF WINNIPEG, CANADA.

AIR-COMPRESSOR.

No. 915,759.

Specification of Letters Patent. Patented March 23, 1909.

Application filed August 28, 1907. Serial No. 390,496.

To all whom it may concern:

Be it known that I, GERALD FOLL, of the city of Winnipeg, in the Province of Manitoba, Canada, machinist, have invented certain new and useful Improvements in Air-Compressors, of which the following is the specification.

My invention relates to air compressors, and the object of the invention is to provide a simple, highly efficient, three cylinder, upright, double acting air compressor, which is evenly balanced and has little jarring, and for its size has a large capacity.

It consists essentially in a suitable set of upright supports or standards, a set of three vertical water jacketed pivotally supported cylinders having peculiarly constructed inlet and outlet ports, a crank shaft carried by the supports, pistons working in the cylinders and operated by the crank shaft, a common lead pipe, flexible hose or tubing connecting the cylinders with the lead pipe, the parts being arranged and constructed as hereinafter more particularly described.

Figure 1 is an end elevation of my compressor. Fig. 2 is a top plan view of the same. Fig. 3 is a rear side view of the invention. Fig. 4 is a vertical cross sectional view through one of the cylinders, the section being taken in the plane as denoted by the line $\bar{X}X'$, Fig. 3. Fig. 5 is an enlarged detailed sectional view showing the manner in which the cylinders are supported.

In the drawings like characters of reference indicate corresponding parts in each figure.

1, 2, are suitable standards, of practically a lathe support form, having feet through which the standard may be bolted to the floor, or any convenient base.

3 are cross plates between the standards, being bolted at their ends at 3' to the standards, it being noted that the standards are in cross section of T form.

4, 5, are side brackets of a U-shape form, bolted at 5' to the ribs of the standards and toward the foot.

6 is a crank shaft having the eccentric pins 6' set at substantially 120° , such crank shaft being carried in bearings 7, formed within the standards, the eccentric pins being placed so that one is midway between

the supports, and the other two, one at each end beyond the supports.

8, 9, and 10 are the cylinders, all of which are identical in construction, and will be described more particularly in detail shortly, the present description simply being for the purpose of showing the manner in which the cylinders are supported. Each cylinder has centrally of its length and diametrically opposing, two lugs 11, formed thereon, and the lugs are bored out and threaded to receive a brass bearing 12.

The standards have each a lower cross arm 13, the positions of which are horizontally in alignment with the brackets 4 and 5, the arms having, centrally between the legs of the standard, each a threaded opening to receive a screw 14, having a square head 15, by which it may be adjusted by a wrench. The other end of the screw is formed with a conical point 16 and the bearing 12 is bored out to receive the conical end of the screw.

17 are adjusting screws of the same form as that 14, such screws passing through threaded openings, respectively, centrally in the brackets 4 and 5. The conical points of these screws pass into the bearings on the cylinder, directly opposite the bearings for the screws 14.

18 are cross bars passing between the cross plates 3, to which they are secured, and have centrally, each, a cross opening in an enlargement 19, to receive a threaded screw 20, of the same form as those 14 and 17. These latter screws work in bearings 12 on the cylinder.

To put the cylinders in position, the two outer ones 8 and 10 are held by the screws 14 and 17, which may be adjusted to any desired tightness in the bearings. The central cylinder 9 is supported by the screws 20, which are, as before described, adjustable.

21 is a combined belt and fly wheel.

To avoid prolixity I will now describe in detail one of the cylinders of the compressor and the piston, it being understood that the others are exactly the same in form.

22 is the cylinder body, having at one side an enlargement 23, bored to form a longitudinal channel 24 for the complete length of the cylinder.

25, 26, are the cylinder heads, the crank end being 25. The heads are held to the

cylinder body by screws 27 passing through the head and into the body, there being four of these to each cylinder head.

28 are two annular rings, one at either end 5 of the cylinder, having an internal thread by which the rings may be screwed on the cylinder body at 29.

30 is an encircling casing around the cylinder, forming a water jacket, such casing 10 being held in place by means of the annular rings 28, which are screwed down tightly on the edges of the casing.

31 is the piston carrying the ordinary split 15 rings, and 32 is the piston rod passing upwardly through the piston head at the crank end.

34 is a stuffing box on the cylinder head, and 35 is a cap screwed over the stuffing box allowing of an opening 37 for the reception 20 of waste, carrying oil.

38 is a drip cock opening to the bottom of the cylinder through the head. The cylinder heads are bored at 39 and 40, to receive brass valve caps 39' and 40' respectively. Those 25 39' have formed at their lower end a seat for the valve 41.

42 are the valve stems of the valve 41, such valve stems finding bearings in the spiders 43, and the cap screws 44, which 30 screw into the valve caps 39'. The latter cap screws have openings 44' to allow air to pass the valve.

45 is a spring between the top of the cap screw 44 and the pin 46 in the end of the 35 valve stem, and serves to keep the valve normally tightly closed.

47 are inlet ports from the valve to the cylinder, such ports being bored through the cylinder heads.

40 The valve caps 40' are screwed into the cylinder heads, directly above and below the longitudinal channel or passage-way 24, and 49 are cap screws fitting the ends of the valve caps.

45 50 are the exhaust valves and 51 the valve seats formed in the cylinder heads directly above and below the channel 24.

52 are the valve stems bearing in the spider 53, carried by the valve cap, and 54 50 are spiral springs encircling the valve stem between the spider and the pin 55, at the end of the stem.

56 are the exhaust ports from the cylinder, being bored through the cylinder head.

55 57 are flexible pipes, screwing at their one end to the cylinder and opening into the channel 24, and connecting at their other end with the lead pipe 58, to which they are secured by a T elbow 59. There are, as will

60 be seen in the drawings, three of these pipes, and they form the leads for the compressed air from the cylinder. Each pipe 57 has located therein, near the cylinder, a valve 60, operating on a valve seat 61 formed in

the pipe. The valve stem 62 is carried by 65 spiders 63 within the pipe.

64 is a drip or blow-off cock, at the end of the main lead pipe 59. The other end of the latter pipe is connected directly to a receiving tank.

70 The piston rods 32 are fastened to the respective eccentric pins 6' by means of the ordinary journals 65.

In order to thoroughly understand the invention I will now describe its operation 75 The rotation of the crank shaft 6 reciprocates the pistons in the cylinders successively. The pivotal suspension of the cylinders by means of the screws allows of the rocking motion necessary to accommodate the piston 80 rod. On the down stroke of the piston, air is drawn into the cylinders through the upper valve 41, and the air in the cylinder forward of the piston is compressed and forced through the lower valve 50, the channel 24, 85 and the valve 60, to the main lead 58, from which it goes to the receiving tank. For the upward stroke of the piston the previously described valve motion is duplicated in the other set of valves, the air being drawn in 90 through the lower valve 41, and the air on the rear side of the piston being compressed to the channel 24, through the upper valve 50. In this way it will be seen the pistons are all double acting.

95 In referring to the drawings it will be noticed that the valves 50 are so placed that when one is forced open the other is closed so that there is no chance for the air to return to the piston chamber. The valve 60 simply is 100 used as a safe guard, and makes the valve 50 more easily operated and more positive. It is necessary, to open the valve 60, that the pressure in the passageway or channel 24 become equal to or greater than the pressure in 105 the pipe 57, or in other words the valve prevents the pressure in the main lead, *i. e.*, the back pressure from the air tank from coming directly on the valves 50, such valves allowing absolutely no back pressure in the cylinder. When using the machine the water jackets on the cylinders may be inter-connected, and any other portion of the machine which it may be found advisable to jacket 110 may be water jacketed.

115 66 are oil cups of any desirable form, feeding to the inside of the cylinder.

Although I have not shown any packing strips between the cylinder head and the cylinder body, it will be understood that whatever is found to be necessary may be used, and also that it may be used in any other places where it may be deemed advisable.

120 What I claim as my invention is:

1. An air compressor comprising a pair of 125 uprights, a crank shaft carried at the upper end of said uprights, cross bars connecting the upper ends together, a U-shaped bracket

secured on the outer side of each upright, a cross bar carried by each upright, cross bars between the bars connecting the uprights together, pivotal points carried by the U-shaped brackets and the last named cross bars and the cross bars carried by each upright, oscillating cylinders carried by said pivotal points, pistons in said cylinders, and connecting means between the pistons and

10 the crank shaft.

2. In a device of the class described the combination with the supporting standards spaced apart by cross plates, the cross plates being inter-connected by cross bars, the 15 brackets to the outer side of the standards and the crank shaft supported by the standards, of an outer set of cylinders and an inner cylinder, having centrally of their length and

diametrically opposing a set of lugs internally threaded to receive a brass bearing, an 20 opposing set of conically pointed adjusting screws carried by the brackets and the standards, and an opposing set of conically pointed adjusting screws carried by the cross bars between the standards, each set of adjusting 25 screws being adapted to engage with the bearings on the cylinders, and reciprocating pistons within the cylinders operated by the crank shaft, said cylinders having oscillating movement as and for the purpose specified. 30

Signed at Winnipeg, in the Province of Manitoba, this 24th day of July 1907.

GERALD FOLL.
